UNITED STATES PATENT OFFICE.

FREDERIC PAYSON REED, OF EAST ORANGE, NEW JERSEY, ASSIGNOR, BY MESNE
ASSIGNMENTS, TO CHARLES C. ORCUTT.

MOISTENING DEVICE.

Application filed February 7, 1921. Serial No. 443,007.

To all whom it may concern:

Be it known that I, FREDERIC PAYSON REED, a citizen of the United States, residing at East Orange, in the county of Essex, State of New Jersey, have invented certain new and useful Improvements in Moistening Devices; and I do hereby declare the following to be a full, clear, and exact description of the invention, such as will enable others skilled in the art to which it appertains to make and use the same.

My invention is an improvement in machines for coating paper and the like, of the character shown and described in my co-pending application Serial No. 241,102, filed June 21, 1918, and Patent No. 1,394,444, and relates especially to devices for moistening the paper prior to the application of the color, to prepare the paper for receiving the color.

An object of the invention is to provide means in connection with a device of the character specified, for applying a film of moisture, as for instance water or liquid color, to one face of the paper, and uniform throughout the extent of the said face, controlled by the relative movement of the applying means and the paper, wherein the quantity of the moisture applied may be varied at will.

Another object is to provide in a device of the character specified, a moistening means in the form of a wiper of absorbent material, feeding from a closed constant level reservoir, having means in connection therewith for admitting a regulated quantity of air, whereby to control the pressure on the liquid in the reservoir and the feed through the wiper.

40 In the drawings:

Figure 1 is a longitudinal section of a part of a paper coating machine provided with the improved moistening device.

Figure 2 is a rear view of the moistening device, with a part in section,

Figure 3 is a plan view of a part of the reservoir,

Figures 4 and 5 are sections on the lines 4-4 and 5-5 respectively, of Figure 3.

50 In the machines forming the subject-matter of the above applications, moisture, as for instance water, is applied to one face of the paper, sheet or web, by means of a roller which dips into the moistening liquid, and the moisture is distributed uniformly over

the sheet, by means of rubbers and squeegees. In the present invention the moisture is applied and simultaneously distributed uniformly over the face of the paper by a single element controlled by the relative movement of the applying means and the paper.

The present embodiment of the invention is shown in connection with a paper coating machine comprising a suitable supporting frame 1, upon which is journaled a reel 2 carrying the web 3 of paper which is to be coated. The paper passes from the reel over suitable tension rollers 4 and 5, to a drum 6 over which the web passes to the means for spattering or striping the paper with color. In the present instance, spattering means is shown, each of the said means consisting of a tank 7 supported by the frame, and a roller 8 is mounted to rotate in the tank, dipping into the color held by the tank. Above and slightly in front of each roller is a shaft 9 mounted to rotate counter to the roller, and carrying series of bristles 10 extending longitudinally of the shaft. These bristles contact with the smooth top face of the roller and flick off little specks of liquid color delivering them upon the traveling sheet or web. Before the paper is spattered or striped with the color, it is necessary that

the face which is to be spattered or striped be provided with a film of moisture and that the film be uniformly distributed throughout the extent of the paper. In the prior applications above mentioned, this distribution was as before stated obtained by rubbing and squeegeeing. In the present invention, the depositing of the film and the distribution of the same, is obtained by means of a wiper 11 of felt or like porous absorbent material. The said wiper is supported by a reservoir 12 of cylindrical form, which is supported by the frame transversely of the traveling sheet of paper, and in front of the first spattering or striping device. This

reservoir has hollow journal pins 13, which are journaled in brackets 14 extending upwardly from the frame, and one of the pins has a handle or crank 15, for convenience in turning the cylinder. The other journal pin is an inlet for the moistening liquid, which may be water, or a suitable liquid color,

where it is desired to coat the paper with a back-ground or body color before spattering or striping. The wiper 11 is held in a slot 110

16 extending longitudinally of the reservoir, and it is clamped in the slot by means of a fixed clamping plate 17, and a movable plate 18. The plate 17 is held to the reservoir at one side of the slot by means of screws 19, and the plate 18 is held to the reservoir at the other side of the slot by means of screws 20. The screws 20 engage notches 21 in that side edge of the plate remote from the slot, 10 and it will be obvious that by loosening the screws the plate may be moved toward and from the plate 17, to clamp or release the wiper.

That journal pin of the reservoir which is remote from the crank or handle has connected therewith a flexible pipe or hose 22, by means of a clamping band or collar 23. The other end of the pipe 22 is connected with the discharge nipple 24 of a tank 25, by means of a band 26 similar to the band 23 beforementioned. The discharge nipple 24 is controlled by means of a valve 27, so that the supply of moisture to the reservoir may be cut off when desired. The reservoir 25 is a constant level reservoir, being continuously supplied with moisture from the tank, and having a discharge nipple 28 which is of the same capacity as the inlet pipe 22. That is the flow through the discharge nipple 28 is the same as the flow from the tank to the reservoir, so that a constant level is maintained in the reservoir. A pipe 29 is connected with the discharge nipple 28, and the discharge end of this pipe 29 has a water seal 30 for preventing the entrance 35 of air to the reservoir.

When the device is operating, the water flowing through the wiper creates a degree of suction in the reservoir, which is fluid tight. As above stated, the discharge or overflow nipple 28 is of a capacity equal to that of the inlet pipe, so that the liquid in the reservoir cannot rise above a predetermined level, that is the level of the overflow. 40 It can however, fall below such level, when there is a flow through the wiper. The inflow into the reservoir is however, regulated in accordance with the demands upon the reservoir by the wiper. Since the overflow 45 is trapped, and no air can enter through the supply pipe, any variation in the level of the liquid will vary the pressure in the air chamber or air space above the liquid. The air which gains admission to the reservoir through the wiper is limited, and not sufficient to permit the desired feed. In order 50 to admit a regulated quantity of air to the reservoir, whereby to control the flow of the moistening liquid through the wiper, I provide a series of openings 31 in that surface of the reservoir which is uppermost 55 when the reservoir is in normal position, and I provide means for regulating the capacity of these openings, whereby to vary the 60 amount of air admitted to the reservoir. The 65

said means is in the form of a slide or valve 32 which has guided movement on the reservoir, and has openings 33 adapted to register more or less with the openings 31 of the reservoir. The slide or valve is provided 70 with longitudinally extending slots 34, which receive headed screws 35 engaging with the reservoir. The slots and screws permit a limited movement of the slide with respect to the reservoir, sufficient to cause the openings 75 31 and 33 to register completely, or to move entirely out of register. The slide moves between undercut guides 37 extending longitudinally of the reservoir wall, and it has a handle 36 for convenience in manipulating 80 the same. A drip pan 38 is arranged in front of the reservoir and below the same, and when the device is not in use, the reservoir may be rotated to bring the free edge of the wiper over the drip pan. 85

The hollow journal pins have threaded engagement with the ends or heads of the reservoir as shown in Figure 4 and the outer end of that pin which engages the hose 22 is preferably threaded or corrugated to prevent displacement of the hose. The end of the discharge nipple 24 of the tank is similarly threaded or corrugated, for a like purpose. 90

It will be obvious that many different 95 methods might be utilized for admitting a regulated quantity of air to the reservoir, in order to control the flow of the moistening liquid through the wiper. As for instance the tank 25 might be a closed tank, and the air admitting valves might be arranged in the tank. With this construction the flow of moistening liquid into the reservoir, and the consequent pressure therein would control the flow through the wiper. 100

I claim. 105

1. In a machine of the character specified, a closed reservoir, a wiper through which the reservoir feeds, means for continuously feeding liquid thereto, said reservoir having a trapped overflow for maintaining a constant level of liquid in the reservoir and an air space above the liquid, and means for regulating the admission of air to the said space whereby to regulate the feed through 110 the wiper. 115

2. In a machine of the character specified, a wiper of absorbent material for engaging the paper to deposit a film of moisture thereon, means for supplying to the wiper a 120 regulated and uniform amount of moistening liquid, said means comprising a closed reservoir with which the wiper communicates, means for feeding liquid to the reservoir, means for preventing the rise of the 125 liquid in the reservoir above a predetermined height, whereby to maintain an air space above the liquid, and means for admitting a regulated quantity of air to the said space. 130

3. In a machine of the character specified, a wiper of absorbent material for engaging the paper, a closed reservoir with which the wiper communicates, means for maintaining a constant head of liquid in the reservoir and an air space above the liquid, and means for admitting a regulated quantity of air to the air space, whereby to control the flow of liquid through the wiper.
- 10 4. In a machine of the character specified, a wiper of absorbent material for engaging the paper to deposit a film of moisture thereon, means for applying to the wiper a regulated and uniform amount of moistening liquid, said means comprising a closed reservoir with which the wiper communicates, means for supplying a regulated quantity of liquid to the reservoir, means for limiting the rise of the liquid in the reservoir to provide an air space above the liquid, means for admitting a regulated quantity of air to the said space, the reservoir having a longitudinally extending slot, the edge of the wiper being received in the slot, and means for clamping the wiper in place.
- 15 5. In a machine of the character specified, a wiper of absorbent material for engaging the paper to deposit a film of moisture thereon, means for applying to the wiper a regulated and uniform amount of moistening liquid, said means comprising a closed reservoir with which the wiper communicates, means for supplying a regulated quantity of liquid to the reservoir, means for limiting the rise of the liquid in the reservoir to maintain an air space above the liquid, means for admitting a regulated quantity
- 20 of air to the said space, the said means comprising a series of openings in the reservoir, and a slide movable on the reservoir over the openings, and having openings adapted to register with those of the reservoir.
- 25 6. In a machine of the character specified, a wiper of absorbent material for engaging the paper to deposit a film of moisture thereon, means for applying to the wiper a regulated and uniform amount of moistening liquid, said means comprising a closed reservoir with which the wiper communicates, means for supplying a regulated quantity of liquid to the reservoir, means for limiting the rise of the liquid in the reservoir to provide an air space above the said liquid, and means for admitting a regulated quantity of air to the said space, the reservoir being mounted to rotate on a horizontal axis to bring the wiper into and out of operative position.
- 30 7. In a machine of the character specified, a wiper of absorbent material for engaging the paper, a closed reservoir with which the wiper communicates, means for maintaining a constant head of liquid in the reservoir, means for admitting a regulated quantity of air to the reservoir, whereby to control the flow of liquid through the wiper, the means for maintaining a constant level in the reservoir comprising a supply tank feeding thereto, the reservoir having an overflow of equal capacity to the inflow from the tank, and said overflow having a water seal.

In testimony whereof I affix my signature.

FREDERIC PAYSON REED.
